CLAIM

The original ornamental design for a lower body garment gusset panel with pointed ends, substantially as shown and described.

DESCRIPTION

FIG. 1 is a perspective view of a lower body garment gusset panel with pointed ends of the present invention, as it may be used in panty hose (the broken lines shown on the lower body garment gusset panel and on the panty hose represent unclaimed features);

FIG. 2 is a front elevational view of the claimed lower body garment gusset panel design;

FIG. 3 is a plan view of the claimed lower body garment gusset panel design;

FIG. 4 is a rear elevational view of the claimed lower body garment gusset panel design; and,

FIG. 5 is a right side elevational view of the claimed lower body garment gusset panel design (the left side elevational view is a mirror image thereof).
